BOOKMARK

Ernest Scognamillo, Bronx, N. Y.

Application August 6, 1932. Serial No. 627,787

5 Claims. (CL 281—42)

This invention relates to a book mark and has for its chief object to provide a device which may be easily and quickly attached to and removed from one of the covers of a book and having 5 means to overlie a leaf of such book and thus to serve both as a marker for indicating the page of the book at which a person has ceased reading the book and to hold such page against being turned while being read, which means may 10 nevertheless be caused, by the turning of the page which it overlies, to move out of the way of such leaf or page and will thereafter be caused to automatically engage the succeeding leaf or page.

The device in its preferred form comprises 15 a clip to straddle one of the covers of a book, an arm carried by such clip to extend substantially parallel to and obliquely of the upper edges of the pages of the book, and a finger flexibly connected to such arm to overlie a leaf or page of 20 the book, which finger, on account of its flexible connection to the arm, may be caused, by the turning of the leaf or page which it overlies, to swing out of overlying relation to said page and then be caused, by its weight and its flexible connection to the arm, to swing back into position to 25 overlie the next succeeding leaf or page of the book.

The invention will be described with reference to the accompanying drawing which illustrates 30 a preferred embodiment of the invention and in which:

Figure 1 is a perspective view of the book mark; Figure 2 is a perspective view of an open book 35 having the book mark attached thereto;

Figure 3 is a view similar to Figure 2 wherein one of the pages of the book is shown as being turned and moving the leaf-engaging finger out of the way of such page.

Figure 4 is a perspective view of a closed book 40 having the book mark applied thereto and with the page-engaging finger positioned over the page at which the reading of the book was discontinued, and

Figure 5 is a perspective view of fragmentary 45 portions of the arm and the finger or index of the book mark.

The device comprises a clasp, generally designated as 2, preferably made of sheet spring steel 50 bent into substantially U-shape, as at 4, to form front and rear clamping jaws 5 and 6. The jaws 5 and 6 are constantly urged toward one another by their connecting portion 4. The clasp 2 is adapted to straddle the upper edge of the rear cover 3 of a book, preferably near the free or 55 outer edge of the cover, as shown in Figures 2,

3 and 4. The jaw 6 is wider than the jaw 5, and carries, adjacent the connecting portion 4, a lug 7 which extends substantially at a right angle to said jaw.

An arm 9 is pivotally connected at one of its 60 ends, as at 8, to the lug 7, to swing on an axis substantially parallel to the jaws 5 and 6 and has a portion 10 adapted, when the jaws 5 and 6 straddle the back cover of the book, to lie along 65 the upper edges of the pages of the book obliquely to such edges.

The opposite end of the portion 10 of the arm 9 is connected to one end of a flexible member 13, shown as a cylindrical spring having one end 12 surrounding and frictionally engaging a nipple 11 extending from said end. The other end 14 of the flexible member 13 is connected to a leaf-engaging finger 17, said end being shown as surrounding and frictionally engaging a nipple 15 on one end of said finger. The finger 17 is curved 70 between its ends as at 16. Since the leaf-engaging finger is curved between its ends, the free terminal portion thereof is normally disposed at an angle to the axis of the arm 9 and in a plane 75 substantially parallel to the jaws 5 and 6 of the clip 2.

When the device is applied to the rear cover of the book with the clasp 2 straddling the upper edge of the cover and its jaws 5 and 6 frictionally 80 engaging the opposite sides of the cover adjacent the free side edge thereof, the arm 9 and flexible member 13 will be disposed adjacent to the upper edges of the pages of the book and obliquely thereto, and the free terminal portion of the finger 17 will overlie the upper portion of a 85 page of the book adjacent the back of the book, with the edge of said page disposed in the curve 16 of said finger as shown in Figures 2 and 4. The resiliency of the flexible member 13 and the 90 weight of the finger 17 are sufficient to normally maintain the finger 17 in engagement with the leaf of the book which said finger overlies and the flexible member 13 is resilient enough to be twisted axially and to then be flexed laterally by the turning of the leaf of the book engaged by the finger 17, so that during the turning movement of such leaf the leaf will first lift the finger 17 in the direction in which the leaf is turned and then ride along and deflect said finger until its edge rides past the free end of the finger, whereupon the weight of the finger 17 and the 95 flexible member 13 will swing the finger 17 back 100 to position to overlie the next page of the book.

I claim:

1. A book mark, comprising a member for at- 110

tachment to one cover of a book, an arm connected at one of its ends to said member to extend substantially parallel to certain edges of the leaves of such book, a flexible member having one of its ends connected to the other end of said arm, said flexible member forming a normally coaxial continuation of said arm, and a finger carried by the other end of said flexible member, said finger having a portion bent laterally of said flexible member and urged by said flexible member in a direction toward the cover of the book to which the first named member is attached.

2. A book mark comprising a member for attachment to a cover of a book, an arm including a rigid portion connected to said member and an elastic portion normally extending in axial alinement with said rigid portion, and a finger extending from said elastic portion to overlie a page 20 of the book and yieldingly urged by said elastic portion toward the cover of the book to which the first-named member is attached.

3. A book mark comprising a member for attachment to a cover of a book, a rigid arm connected at one end to said member to extend past certain edges of the leaves of such book, a spiral spring having one of its ends connected to the other end of said arm and normally extending in axial alinement with said arm, and a finger 30 extending from the other end of said spiral spring, said finger having a portion bent at an angle to the axis of said spring to contact with a page of the book and yieldingly urged by said spring toward the cover of the book to which the first-named member is attached.

4. A book mark comprising a member for attachment to a cover of a book, a rigid arm movably connected at one of its ends to said member for adjustment into a position obliquely of certain edges of the pages of the book, an elastic member secured at one of its ends to the other end of said rigid arm and normally extending in axial alinement with said rigid arm, and a finger bent between its ends and extending from the other end of said elastic member and yieldingly urged by said elastic member toward the cover to which the first-named member is secured with its bend over the edge of a page of the book and its terminal portion overlying such page.

5. A book mark comprising a member for attachment to a cover of a book, a rigid arm, means connecting one end of said arm to said member for adjustment about an axis substantially parallel to the pages of the book, said means holding said arm portion against turning movement about its longitudinal axis and also against movement away from said edges of the pages, a spiral spring fixed at one of its ends to the other end of said rigid arm and normally extending in axial alinement with said arm, and a finger secured at one 100 of its ends to the other end of said spiral spring and having its terminal portion disposed at an angle to the axis of said spring to normally overlie a page of the book, said spiral spring yieldingly holding the terminal portion of the finger in 105 contact with a page of the book and constantly urging it toward the cover to which said member is secured.
